SAWDUST HOPPER

Emil Zimmerman, Everett, Wash.

Application June 11, 1941, Serial No. 397,584

10 Claims. (Cl. 259—38)

Sawdust, so-called, is fed to sawdust burners from hoppers having upwardly flared walls, usually open at their top and having a restricted throat at the bottom. This sawdust includes in large measure hogged particles of wood, small chips, and the like, and tends to bridge and clog within the hopper, particularly when it is somewhat wet. The same tendency to bridge and clog within an upwardly flared hopper is encountered in handling other substances. It is impracticable 10 to provide mechanically operated means to continually break up the bridging and clogging tendencies, and because of these tendencies the trouble-free, continuous operation of sawdust burners has not heretofore been fully attained. This tendency, therefore, presents a serious problem to the satisfactory use of sawdust burners.

Various partition walls have been provided within such sawdust hoppers, which are intended to eliminate these tendencies without mechanically induced movement, but none of them have fully solved the problem. This, I have discovered, appears to be due largely to the relationship between such inserted partitions and the flared walls of the hopper. While such partitions may divide the hopper space into smaller chambers, and while certain of these chambers may at one time or another have a shape which permits free movement of the sawdust downwardly, without clogging or bridging, usually they further restrict the size of the effective throat opening, and a time will arrive in the process of emptying the hopper when such partition walls form with adjacent hopper walls, not downwardly flared, but rather upwardly flared chambers, thereby, as in the case of the hopper initially, forming a storage space or chamber wherein bridging and clogging of a material part of the capacity of the hopper occurs.

According to the present invention clogging and bridging of the sawdust or other contents of the hopper is prevented, without any mechanically induced movement, and therefore simply and cheaply, by pendant and freely swinging partition strips which are arranged in a novel manner, so that, purely by the manner in which the hopper is filled and emptied it tends to present always to the throat a chamber which is larger at its bottom than at its top, or at least not greater in size at its top than at its bottom, and having a bottom cross section which does not materially extend outside the outline of the hopper throat.

It is a further object to provide a device of this nature which will operate automatically, solely by reason of the formation and weighting of the

elements, which is simple and inexpensive, which is not likely to get out of order, and which may be arranged for ready removal, in case it is desired to have access to the interior of the hopper.

With these and other objects in mind, as will appear hereafter in greater detail, my invention comprises the novel combination of such a hopper with such clog-preventing means, and the novel clog-preventing assembly per se, as shown in the accompanying drawing, described in this specification, and as will be more particularly pointed out by the claims which terminate the same.

In the accompanying drawing I have shown my invention incorporated in a hopper, all in a representative form as now preferred by me.

Figure 1 is a vertical section through the hopper, illustrating the clog-preventing device in position therein, and Figure 2 is a plan view of the same.

The hopper as shown is largely conventional. It is shown with upwardly flared walls 1, leading upwardly from and defining the throat 2 at the bottom, and open at its top. While dimensions of course are immaterial, it will be helpful in understanding the principles of the invention if representative dimensions are given. Thus, for instance, the throat may be a square 10 inches long on each side. The hopper at its top may be square and 26 inches along each side, and it may be 36 inches high. It can be seen that the interior of the hopper converges rather sharply downwardly to the hopper throat, and that the sawdust would tend to bridge and clog as it would tend to move downwardly within this hopper.

Adjacent the upper part of the hopper, as a convenient support is a transverse rod 8. Supported upon this rod or any equivalent means is a frame 3, which when the throat is rectangular would normally be rectangular also; that is to say, the frame 3 is similar in shape to the shape of the throat 2. If the throat is round the frame 3 might still be rectangular or square or even hexagonal. Preferably the frame 3 is slightly less in extent, as viewed in plan, than the outline or margin of the throat, and the frame is located vertically above the throat.

Pivotedly hung upon each side of this frame 3 is a partition strip. These partition strips, to distinguish them, have been designated 4, 5, 6, and 7, although they are intended to be identical in form and arrangement. Each one is provided with a sleeve 9 at its upper end, fitting about its side of the frame 3, and forming a free pivot support for the strip. Each strip is preferably so

weighted, or its weight is arranged in such fashion, that its lower end tends to swing somewhat outwardly; thus the strips do not hang precisely vertically, but rather are inclined slightly outwardly. This has been somewhat exaggerated in the drawing for purposes of clearer illustration.

With relation to the height of the hopper in which this assembly is to be supported, the strips 4, 5, 6, and 7 are of such length that when the frame 3 is supported upon the rod 8 the strips hang downwardly from the top of the hopper almost to the throat 2. They stop somewhat short of the throat at their lower ends, but are of sufficient length that if swung materially outwardly from their freely hanging positions they will contact the flared side walls 1 of the hopper, and will be thereby prevented from swinging farther. To express it differently, the pattern defined by the lower end of the partition strips, when hanging freely, does not materially extend outside the outline of the throat, and is closely above the throat; even if the partition strips should be swung outwardly into contact with the side walls of the hopper their pattern still does not materially extend outside the pattern or outline of the throat.

The strips are preferably of a width, at least at their bottoms, which is appreciably less than the length of the frame 3 on the corresponding side of the frame.

Thus formed, arranged, and assembled, the partition strips 4, 5, 6, and 7 cooperate to define between them a central chamber which at its bottom is not materially larger than the outline of the throat 2, and which upwardly therefrom progressively decreases in cross-sectional extent. This central chamber is directly in line with the throat 2, to discharge thereinto. Surrounding this central chamber are, in the present instance, four wedge-shaped chambers defined between each of the partition strips and the adjacent upwardly flared hopper wall. These outer wedge-shaped chambers are, of course, smallest at their bottoms.

In using the invention the clog-preventing assembly, consisting of the frame 3 and the strips 4, 5, 6, and 7, is placed within the hopper, suitably supported at the upper end of the hopper. The strips hang freely, and thereby diverge slightly outwardly at their lower ends. The hopper is now filled from the top in the normal manner. It is not necessary to take any care to hold the partition strips in any particular position; they will normally remain approximately in their freely hung position, for sawdust will fall, not only in the central chamber, but also in the surrounding chambers, as the hopper is being filled. Now, as the sawdust is consumed in the burner which is below the throat 2, it is replenished by material from above. The material from above comes at first only from the central chamber, and since this central chamber has its largest cross section adjacent the throat, and not materially greater in extent than the outline of the throat, the sawdust falls freely from this central chamber without any tendency to clog or to bridge. Such tendency arises only when there is a downward constriction in the chamber from which the sawdust drops.

The central chamber will continue to empty until it is largely emptied. Some sawdust will fall in from the outside chambers, especially at the open corners, but these outside chambers will not empty to a large degree. Finally the pressure from one of the wedge-shaped outer

chambers, inwardly upon its partition strip, will overcome the resistance of the material within the bottom of the emptying central chamber, and this particular partition strip will swing inwardly. In doing so, it vigorously breaks up clogging in the vicinity of the throat. It may swing all the way across the central chamber to contact, for instance, the strip 6 with the strip 4, in the initial position of the latter, as shown at A. On the other hand, both the strip 4 and the strip 6 may each swing inwardly, and may meet in an intermediate position, as shown at B.

In either case the chamber defined between the partition strip 6 and its adjacent hopper wall is materially increased in volume, and its bottom is increased in cross-sectional extent until it is larger than its top. Its bottom extent is not materially greater than the extent of the margin of the throat 2, for the length of the partition strips is so chosen that they cannot swing far past the opposite side of the throat. Accordingly there is now provided a further chamber at the right, which progressively decreases in cross sectional extent upwardly, and which is not materially larger at the bottom than the extent of the throat. This chamber will empty freely as originally did the central chamber, and in time this chamber will be deformed again by pressure against some other partition strip, the sawdust above the throat will be stirred, and each new chamber will be suddenly enlarged in volume, and will have its bottom increased in plan extent, so that it will discharge freely through the throat.

It is conceivable that all four of the partition strips 4, 5, 6, and 7 may be simultaneously swung inwardly, as shown in the dot-dash lines C. There would still be the effect of a sudden increase in the volume of each of the outer chambers, a stirring of sawdust at the throat, and an increase in the extent of the bottom opening of each such outer chamber. These increases, it has been found, are sufficient to permit discharge from these outer chambers without clogging, and at some point in the operation one such chamber will discharge more than the others, and will then be constricted with corresponding enlargement of another chamber, which in turn will permit freer discharge from this other chamber.

It has been found that this arrangement will operate continuously and with entire satisfaction. It is extremely simple and inexpensive, and there is nothing to get out of order. If it is desired to gain access to the interior of the hopper the entire assembly may quickly be lifted from the open top of the hopper, even if the hopper is filled, leaving the hopper interior free and clear.

It is in the provision of a central chamber, shaped and positioned for free and non-clogging discharge, and substantially complete discharge, directly through the throat, in advance of any substantial discharge from other chambers, and in the arrangement of the partition strips in such manner that with the collapse of the central chamber one of the outer chambers is immediately enlarged at its bottom and in its volume, for similar free discharge, that this invention is to be distinguished from other hopper-partitioning arrangements.

What I claim as my invention is:

1. In combination with the upwardly flared walls of a sawdust hopper or the like, having an

open top and a smaller open throat, a plurality of partition strips freely pivotally hung in the upper part of the hopper in a pattern similar to and located directly above the outline of the throat, said partition strips being weighted to diverge slightly downwardly, to define between them a central chamber having its largest cross-section at its bottom not materially extending outside the outline of the throat, and progressively diminishing in cross-section upwardly and to define surrounding wedge-shaped chambers between each partition strip and the adjoining hopper wall.

2. In combination with the upwardly flared walls of a sawdust hopper or the like, having an open top and a smaller open throat, a plurality of partition strips freely pivotally hung in the upper part of the hopper in a pattern similar to and located directly above the outline of the throat, said partition strips being weighted to diverge slightly downwardly, and of a length to contact the hopper wall, when outwardly swung, adjacent the throat, said partition strips cooperating with each other, when hanging freely, and with the adjacent hopper walls, to define between them a central chamber having no cross-section which materially extends outside the outline of the throat, and which increases in cross-section from its top downwardly, and to define surrounding wedge-shaped chambers between each partition strip and each adjacent upwardly flared hopper wall.

3. In combination with the upwardly flared walls of a sawdust hopper or the like, having an open top and a smaller open throat, a plurality of partition strips freely pivotally hung in the upper part of the hopper in a closed pattern, and located directly above the throat, said partition strips being weighted to diverge slightly downwardly, and of a length to contact the hopper wall, when outwardly swung, adjacent the throat, and of a width at their bottoms materially less than the corresponding distance across the throat, said partition strips cooperating with each other, when hanging freely, to define between them a central chamber having no cross-section at its bottom which materially extends outside the outline of the throat, and having all cross-sections above its largest cross-section of progressively decreasing extent, and said partition strips each further cooperating, when hanging freely, with the adjacent flared hopper wall to define an outer wedge-shaped chamber which has its smaller end downward.

4. In combination with the upwardly flared walls of a sawdust hopper or the like, having an open top and a smaller open throat, a plurality of partition strips freely pivotally hung in the upper part of the hopper in a closed pattern, and located directly above the throat, said partition strips being weighted to diverge slightly downwardly, and of a length to contact the hopper wall, when outwardly swung, adjacent the throat, and of a width at their bottoms materially less than the corresponding distance across the throat, said partition strips cooperating with each other, when hanging freely, to define between them a central chamber having no cross-section at its bottom which materially extends outside the outline of the throat, and having all cross-sections above its largest cross-section of progressively decreasing extent, and said partition strips each further cooperating, when hanging freely, with the adjacent flared

hopper wall to define an outer wedge-shaped chamber which has its smaller end downward, each partition strip being further so located at their pivoted upper ends, with relation to the adjacent hopper wall, that when its lower end swings inwardly, upon substantial emptying of the central chamber, into contact with a partition strip opposite, the corresponding outer chamber will have a width at its bottom not materially less than the spacing of the strip's pivoted upper end from the adjacent hopper wall.

5. A clog-preventing assembly for disposition within a flared-wall hopper, comprising a plurality of pendant strips disposed in a closed pattern, and means supporting the strips from their upper ends for free swinging movement, each independently of the others.

15 6. A clog-preventing assembly for disposition within a flared-wall hopper, comprising a plurality of pendant strips disposed in a closed pattern, and means supporting the strips from their upper ends for free swinging movement, each independently of the others, said strips being weighted to hang with their free lower ends more greatly spaced than their pivoted upper ends.

20 7. A clog-preventing assembly for disposition within a flared-wall hopper, comprising a plurality of pendant strips disposed in a closed pattern, and means supporting the strips from their upper ends for free swinging movement, each independently of the others, said strips being weighted to hang with their free lower ends more greatly spaced than their pivoted upper ends, said strips being of a length, relative to the hopper with which they are used, to extend from a suitable support in the upper part of the hopper downwardly to a point adjacent the restricted bottom throat of the hopper.

25 8. A clog-preventing assembly for disposition within a flared-wall hopper, comprising a plurality of pendant strips disposed in a closed pattern, and means supporting the strips from their upper ends for free swinging movement, each independently of the others, said strips being weighted to hang with their free lower ends more greatly spaced than their pivoted upper ends.

30 9. A clog-preventing assembly for disposition within a flared-wall hopper, comprising a rectangular horizontal frame, a pendant strip of sheet metal or the like freely pivotally mounted upon each side of said frame, and weighted to swing outwardly at its lower end, each strip being narrower at its lower end than the length of its side of the frame.

35 10. In combination with the upwardly flared walls of a sawdust hopper or the like, having an open top and a smaller open throat, a plurality of partition strips freely pivotally hung in the upper part of the hopper in a pattern similar to and located directly above the outline of the throat, said partition strips defining between them a central chamber having no cross-section which materially extends outside the outline of the throat, and said partition strips also cooperating with the adjacent hopper walls to define wedge-shaped chambers surrounding the central chamber, and each capable of merging thereinto at the bottom by inward swinging of the corresponding partition strip, after substantial emptying of the central chamber, under pressure of the material retained in such wedge-shaped chamber.

EMIL ZIMMERMAN.
